Primary Examiner — Alison M Ofstun

(57) **CLAIM**

The ornamental design for a wireless hair curler, as shown and described.

DESCRIPTION

FIG. 1 is a perspective view of a wireless hair curler showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

In the drawings, the evenly spaced broken lines illustrate portions of the wireless hair curler that form no part of the claimed design.
